UNITED STATES PATENT OFFICE.

JOHN S. O'CONNOR, OF WHITE MILLS, PENNSYLVANIA, ASSIGNOR OF ONE-HALF TO LOUIS J. DORFLINGER, OF SAME PLACE.

APPARATUS FOR SUPPLYING ABRADING AND POLISHING MATERIAL TO CUTTING AND POLISHING TOOLS.

SPECIFICATION forming part of Letters Patent No. 283,273, dated August 14, 1883.

Application filed June 23, 1883. (No model.)

To all whom it may concern:

Be it known that I, JOHN S. O'CONNOR, of White Mills, in the county of Wayne and State of Pennsylvania, have invented a new and useful Improvement in Apparatus for Supplying Abrading and Polishing Material to Cutting and Polishing Tools; and I do hereby declare that the following is a full, clear, and exact description of the same.

10 In the process of manufacturing fine cut glassware the operations of cutting and polishing are performed by a revolving wheel run at high speed, in contact with which the glass article is held by the operator. In the process of polishing, the periphery of the wheel must be constantly supplied with polishing material, as otherwise the heat generated by the friction would crack the glass and ruin the articles. The method commonly employed in 15 glass-works is to have the polishing-paste supplied to the wheel by a boy with a brush, under the supervision of the cutter. This method, besides entailing the expense of an additional operative, is objectionable, because carelessness or inattention on the part of the boy may ruin valuable articles of glassware, and a certain percentage of loss from this cause occurs in all glass-factories.

20 My invention relates to means for supplying polishing material to the polishing-tool; and its object is to apply such material by means of a connected automatic mechanism under control of the operator.

25 My invention consists, first, in combining with the polishing-tool and positively-operated paste-supplying devices means under control of the workman for throwing such devices out of and into gear with the driving-power; further, in combining with the polishing-tool a brush revolving so as to come in contact therewith, and a supply or receptacle for polishing-paste or other material; further, and finally, in the peculiar and improved construction of the apparatus and its various parts, as 30 fully hereinafter described and claimed.

35 In the drawings, Figure 1 is a cross-section through the paste-receiver, showing the driving-shaft and polishing or cutting tool in elevation. Fig. 2 is a perspective of the paste-applying mechanism upon a larger scale. Fig. 40 3 is a similar view of the whole apparatus.

In Fig. 1, A represents a frame-work of any suitable kind, and B is a shaft running in adjustable boxes *a a*. Upon this shaft is mounted the polishing or cutting wheel C, of ordinary construction. The shaft and wheel are driven by a belt from the pulley *b* to any suitable power. Upon two of the cross-beams of the frame is supported a box, D, within which is held a box, D'. The box D' is movable 55 within the box D, and is made water-tight to hold the polishing-paste.

The devices for applying the paste to the wheel are shown in detail in Fig. 2.

F represents a standard composed of arms 65 *f f*, having set-screws for attachment to a support. Formed with this standard are upwardly-projecting arms G G, the top of each of which is flattened and formed into a half-bearing for the transverse shaft H. The bearings are completed by boxes *g g'*. Running loosely on the shaft H is a cone-pulley, I, which is connected by a round belt, *h*, to a driving-shaft. (Not here shown.) Upon one side of the pulley is a flanged or grooved boss, *i*. The 70 box *g'* is extended to form a plate, *j*, upon which slides a bar, *k*, passing through a guide, *l*. The bar *k* has a finger, *m*, which engages with the flange in the boss *i*, and such bar *k* is moved longitudinally by a pivoted hand-lever, *J*. Upon the opposite side of the pulley I is secured one half of a toothed box-clutch, K. The opposite half, K', is keyed upon the shaft H just within the bearings. As 75 the clutch K revolves constantly with the pulley I, it is clear that the movement of such pulley may be communicated to the shaft by sliding the pulley on the shaft and locking the clutches. The shaft H is extended beyond the bearing *g*, and upon it is adjustably secured, by a set-screw, *n*, a holder, L. In this holder is adjustably secured the handle of a brush, M, the construction allowing the brush to be adjusted both vertically and laterally. The brush will thus revolve with the shaft or 80 remain stationary, according to the position of the clutches.

85 This apparatus, as thus described, is mounted upon the edge of the box D, as shown in Fig. 3, and the inner box partly filled with 90 the polishing-paste. The brush is so adjusted that it will dip into the paste at each revolution of the clutches.

tion, and when in gear will also come in contact with the polishing-wheel, keeping it constantly supplied with polishing material, without any attention or care on the part of the operator. As each article is finished, or at will, it is an easy matter to move the lever and disengage the clutches, when the revolution of the shaft and brush will cease. The brush ordinarily revolves at a speed of sixty revolutions per minute.

Having described my invention, I claim—

1. Combined with a cutting or polishing tool, a device for supplying polishing material to such tool, mechanism for operating such device, and means under control of the operator for throwing such device into and out of gear with the driving mechanism.
2. Combined with a polishing-tool, a reservoir of polishing material and a revolving brush, operated by mechanism substantially as described, so as to supply the tool with polishing material at intervals.

3. Combined with a polishing-tool reservoir to contain polishing material, a vertically and laterally adjustable brush, and mechanism, substantially as described, for causing such brush to revolve.

4. The shaft H, in combination with the loose sliding pulley I, the locking-clutch, the revolving brush, the polishing-paste receptacle, and the polishing wheel or tool.

5. The shaft H, loose pulley I, having grooved boss, the sliding bar and operating-lever, the clutches K K', and the brush and polishing-tool.

In testimony whereof I have signed my name to this specification in the presence of two subscribing witnesses.

JOHN S. O'CONNOR.

Witnesses:

W. H. DIMMICK,
J. B. ELDRED.
